US00D968420S

(12) **United States Design Patent** (10) **Patent No.:** **US D968,420 S**
Huh et al. (45) **Date of Patent:** **** Nov. 1, 2022**

(54) **DISPLAY SCREEN OR PORTION THEREOF
WITH GRAPHICAL USER INTERFACE**

(71) Applicant: **Samsung Electronics Co., Ltd.,**
Gyeonggi-do (KR)

(72) Inventors: **Taekyung Huh**, Gyeonggi-do (KR);
Soyoung Yun, Gyeonggi-do (KR)

(73) Assignee: **SAMSUNG ELECTRONICS CO., LTD.**, Gyeonggi-Do (KR)

(**) Term: **15 Years**

(21) Appl. No.: **29/692,961**

(22) Filed: **May 29, 2019**

(30) **Foreign Application Priority Data**

Jan. 4, 2019 (KR) 30-2019-0000541

(51) **LOC (13) Cl.** **14-04**

OTHER PUBLICATIONS

Unpublished Design U.S. Appl. No. 29/473,401, filed Nov. 21, 2013; applicant: Microsoft Corporation (Claims priority to KR Design Registration No. 30-0770071; cited above).

Primary Examiner — Daniel J Domino

(74) *Attorney, Agent, or Firm* — Cantor Colburn LLP

(57) **CLAIM**

The ornamental design for a display screen or portion thereof with graphical user interface, as shown and described.

DESCRIPTION

FIGURE is a front view of a display screen or portion thereof with graphical user interface showing our new design.

The outer perimeter illustrated by even-dash broken lines represents display screens or portions thereof and forms no part of the claimed design. The remaining even-dash broken lines illustrating portions of the graphical user interface form no part of the claimed design.
